UNITED STATES PATENT OFFICE.

JAMES N. MITCHELL, OF WASHINGTON, DISTRICT OF COLUMBIA, ASSIGNOR OF ONE-THIRD
TO SAM DE NEDREY, OF WASHINGTON, DISTRICT OF COLUMBIA.

COMBINED MATCH-SAFE AND CIGAR-CUTTER.

No. 909,441.

Specification of Letters Patent.

Patented Jan. 12, 1909.

Application filed January 14, 1908. Serial No. 410,854.

To all whom it may concern:

Be it known that I, JAMES N. MITCHELL, a citizen of the United States of America, residing at Washington, in the District of Columbia, have invented new and useful Improvements in a Combined Match-Safe and Cigar-Cutter, of which the following is a specification.

This invention relates to combined match safes and cigar cutters, and one of the principal objects of the same is to provide simple and efficient means for delivering matches one at a time from the safe, and at the same time to provide means whereby as the match is delivered the cutter is operated for cutting off the end of the cigar.

Another object of the invention is to provide a simple, reliable and convenient device for delivering matches singly and cutting the tip from a cigar at the same time.

These and other objects may be attained by means of the construction illustrated in the accompanying drawings, in which,—

Figure 1 is a vertical section taken through the match safe. Fig. 2 is a front elevation of the same. Fig. 3 is an enlarged detail view, showing the delivery end of the match safe with the lever operated to release a few matches from the column to operate the cigar cutter. Fig. 4 is a detail perspective view of the combined lever, match tray and cigar support. Fig. 5 is an end elevation of a modified form of lever and match tray. Fig. 6 is a perspective view of the match container or magazine. Fig. 7 is a front elevation of the modification shown in Fig. 5.

Referring to the drawing for a more specific description of my invention, the numeral 1 designates a suitable base provided with an aperture 2 for suspending the same from a nail or hook. Secured to the base 1 is a plate 3 having a forwardly extending flange 4 at its upper end and side flanges 5.

The match container or magazine comprises, as shown in Fig. 6, a back 6, a top 7, sides 8 and an inclined bottom 9. The sides 8 are disconnected from the bottom, and the lower ends of the sides are rounded, as shown at 10. This magazine or container 50 may be readily withdrawn from the plate 3 by lifting the same from the position shown in Fig. 1. When it is desired to fill the magazine an ordinary paper match box can have its cover removed and placed within the magazine and reversed to deposit all the matches

from the box into the magazine. Secured to the lower ends of the side flanges 5 is a curved front plate 11, which at its lower end provides a restricted opening 12 for a single match. Secured to the plate 11 by rivets 13 is a cigar cutter 14, said cigar cutter having a beveled cutting edge 15.

The combined operating lever, match tray and cigar support consists of an inwardly bent upper end 16 forming a cam-like projection, and pivot bearings 17 are formed at the sides of the projection 16. A pivot pin 18 extends through the pivot bearings 17, and the ends of said pin are supported in the sides of the plate 11. The match tray is formed by the curved lower terminal ends 19, said ends being cut away in the center, as at 20, to form a finger hold for the match. A curved plate 21 is formed on or secured to the lever, and at its upper end the plate 21 carries a trough-like cigar support 22 which may be formed by cutting away the plate 21 and bending the support upwardly, as shown in Fig. 3. A hole 23 is formed in the plate 21, and through this hole the thick end of the cigar is inserted, and when the lever is raised to the position shown in Fig. 3, the cutter 14 is moved past the opening 23 and severs the tip from the cigar. At the same time the cam-like projection 16 releases a match from the column and deposits it into the tray 19.

Should it be desired to use the match box without the cigar cutter, the structure shown in Figs. 5 and 7 may be utilized. The cam projection 16^a is identical with the projection 16, and the pintle bearings 17^a are also like the bearing 17. Three members *a* and *b* project downwardly from the pintle bearings, the two arms *a* being bent upward to form a tray and the central arm *b* being bent downward, as at *c* to form a finger hold for operating the lever and releasing the match.

From the foregoing it will be obvious that my match safe and cigar cutter is of simple construction, will operate reliably to deliver matches one by one, and at the same time cut the tip end from the cigar; that the device may be manufactured at slight cost; that advertising may be used upon the outer surface of the container 6, and that the device is reliable, strong and efficient in use.

Having thus described the invention, what is claimed as new, is:—

1. In a device of the character described, a match magazine, a cam-lever for feeding

matches one at a time from said magazine, a match tray formed on said lever, a curved arm extending upward from said match tray, a cigar support on said curved arm, the latter being provided with an aperture for the end of the cigar, and a cutter secured to the device and adapted to pass the aperture in the operation of the lever, substantially as described.

10 2. In a device of the character described, a match magazine having a restricted outlet opening for the matches, a cam lever pivoted in said opening and provided with a cam for feeding one match at a time through said

opening, a match tray formed upon said lever, a curved arm extending upward from said match tray, a cigar support on said arm, the latter being provided with an aperture for the end of the cigar, and a cutter secured to the front of the match magazine adapted to coöperate with the curved arm to cut the tip end of a cigar.

In testimony whereof I affix my signature in presence of two witnesses.

JAMES N. MITCHELL.
